(57) **CLAIM**

The ornamental design for a faucet handle as shown and described.

DESCRIPTION

FIG. 1 is a perspective view of the claimed design; FIG. 2 is a front view of the claimed design shown in FIG. 1; FIG. 3 is a rear view of the claimed design shown in FIG. 1; FIG. 4 is a side view of the claimed design shown in FIG. 1; FIG. 5 is another side view of the claimed design shown in FIG. 1; FIG. 6 is a top view of the claimed design shown in FIG. 1; and, FIG. 7 is a bottom view of the claimed design shown in FIG. 1.

The ornamental design which is claimed is shown in solid lines in the drawings. The broken lines are included for the purpose of illustrating portions of the article and form no part of the claimed design. Broken lines formed by equal length dashes show unclaimed subject matter. Broken lines formed by unequal length dashes (i.e., dash-dot) define bounds of the claimed design.

1 Claim, 6 Drawing Sheets
